UNITED STATES PATENT OFFICE.

AXEL W. CARLSON, OF WORCESTER, MASSACHUSETTS, ASSIGNOR TO CARLING TURBINE BLOWER CO., OF WORCESTER, MASSACHUSETTS, A CORPORATION OF MASSACHUSETTS.

METHOD FOR MAKING TURBINE ROTORS.

Application filed February 23, 1918. Serial No. 218,860.

To all whom it may concern:

Be it known that I, AXEL W. CARLSON, a citizen of the United States, residing at Worcester, in the county of Worcester and 5 State of Massachusetts, have invented certain new and useful Improvements in Methods for Making Turbine Rotors, of which the following is a specification.

My present invention relates to improvements in the method for producing rotors for elastic fluid turbine engines; the objects being to render the production thereof more economical and efficient.

Another object is to provide an efficient, 15 economical method of supporting the series of vanes and band in properly assembled circular shape, and for maintaining the same in such relatively fixed relation as a unitary element conditioned for handling, 20 temporary storage or transportation, preparatory to their subsequent convenient placement for facilitating the wheel casting operations; said vanes being primarily assembled in circular form, concentrically 25 clamped, and externally surrounded and embedded in a complete annulus of core-material applied and formed thereon, as more fully hereinafter set forth.

It will be understood that I do not claim 30 the idea of attaching vanes or buckets of turbine rotors by casting or cast joints, nor broadly, the employment of a metal band having holes therethrough for receiving and spacing the shanks of the vanes; but my 35 invention relates to the peculiar method illustrated in the drawings and specifically set forth in the following description; the particular subject matter claimed being definitely expressed in the summary.

40 In the accompanying drawings, Fig. 1 represents a cross section of a turbine rotor; the right hand half of the view showing it in the casting mold. Fig. 2 represents a plan view, the quarters taken at different 45 levels; the upper portion showing the rotor as completed; the right hand portion showing the structure of the lower clamp plate and a section of the core-box at line X on Fig. 3; the left hand portion showing the 50 core with the buckets or vanes embedded therein, and the lower portion showing the top of the core-box. Fig. 3 represents a vertical central section of the combined core-box and clamp plates; one side showing the

core as formed therein, and the other side 55 showing the core-forming space with the rotor vanes supported therein ready for receiving the core material. Fig. 4 represents an end and front of one of the buckets or vanes, drawn to larger scale. Fig. 5 represents a side and cross section of a portion of the perforated circular band for spacing the vanes and forming the face of the rotor wheel, and Fig. 6 represents a side and cross section of a portion of the hoop for bracing 60 the outer ends of the radial vanes.

Referring to the drawings, numeral 1 denotes the body disk or wheel of a turbine rotor, and 2 indicates the buckets or vanes radially disposed about the periphery of the 70 wheel for receiving the impelling force of the impelling fluid. Said vanes are made of suitable composition metal, such as heretofore employed in turbine buckets; and are individually formed substantially as shown 75 in Fig. 4, each having at its inner end transverse offsets or shoulders 4, and a longitudinally projecting reduced shank 5, preferably proportioned approximately as indicated, and provided with notches or grooves 80 across the sides. At their outer end the vanes are best formed with endwise projecting lugs 6 at the respective corners, with an intervening flat end surface.

In my method of manufacture the entire 85 series of vanes are fixedly enveloped, in the peculiar manner specified, within a complete annulus of core material. For this purpose I preferably employ the means illustrated in Fig. 3, but claimed in a separate application. In said means the numeral 10 indicates an annular core-box, and 12 a circular clamp-plate adapted to be concentrically supported within the box 10 by an offset or shoulder 11, or by other efficient 95 means. 13 indicates the upper plate of the clamp formed of equal diameter to the plate 12, and superposed thereon with its under surface counter-matching the upper surface of the lower plate; their peripheral 100 edges being approximately upright, or slightly inclined from their junction line outward. The adjacent faces of the clamp-plates 12 and 13 are adapted for receiving the tongues or shanks 5 of the vanes 2, and firmly clamping the same in position when the two clamp-plates 12 and 13 are closed together; said plates having screws or bolts 105

16 arranged therein whereby the clamp can be conveniently tightened and released, as desired. The combined core-box and clamping devices, as a means, is made the subject 5 of a divisional application, Serial No. 229,729; filed April 20, 1918.

The diameter of the clamp-plates 12 and 13 is made the same as the required diameter for the rotor wheel casting, while the thickness 10 of said plates together is such as to give the required depth of core.

The circular band of metal 20, is preferably a thin strip or ribbon of copper or steel about one-sixteenth inch, more or less, in 15 thickness and of a width equal to or slightly greater than the rim 7 of the wheel 1. Said band is provided along its medial line with a series of perforations or holes 21 formed therethrough, of a shape corresponding with 20 the cross section shape of the shanks 5 of the vanes, and spaced to correspond with the desired series spacing of the vanes about the circumference of the rotor. The diameter of the circular band 20 is such as will fit 25 closely, but removably, about the peripheral faces of the adjacent clamp plates 12 and 13, with its openings 21 coincident with the clamp-spaces 15.

According to my improved method the 30 band 20 is primarily disposed about the periphery of the circular clamp-plates and thereby supported in accurate circular form; said band being arranged around the clamp-plates when the latter are slightly separated, 35 sufficient for insertion of the shanks 5 upon the inner ends of the vanes. The shanks of all the vanes are then inserted respectively through the openings 21 in the band, into the space or spaces 15 between the clamp- 40 plates, as at 23, Fig. 2; the shoulder 4 resting against the exterior of the band, and the several vanes standing out radially at their respective spaced positions. The screws 16 are then turned down firmly clamping the 45 shanks in position and retaining the vanes in their proper relation. The clamp-plates are then placed within the circular-box 10, with the clamped vanes projecting outward within the annular space 24 between the edges of 50 the clamp-plates and rim of the box 10. Said space is then filled with core material completely encasing the vanes 2 and band 20 therein, and forming a complete annular core 25 in which the vanes and band are 55 retained at their required position. The top of said core is leveled off with the cover 17 of the box. A metal ring or hoop 18 of round or flat wire may, when desired, be embedded in the material for reinforcing 60 the core.

The clamp-plates 12 and 13, together with the formed core 25, are then removed from the box 10; the clamp screw 16 turned out and the clamp-plates taken off, leaving the 65 band 20 retained in the core with the shanks

5 of the vanes 2 cleanly projecting inward from the inner face of the band, as best shown at 5 on Fig. 2. This circular core is baked to give it proper consistency about the embedded vanes, and forms a complete cylindrical annulus. 70

A casting mold 26 of molding sand is formed in the flask 27, by the use of a suitably shaped pattern in the usual manner of foundry practice. When the pattern is removed from the sand, the circular core containing the band and the series of vanes 2 is placed in the mold with the shanks projecting inward within the matrix. The molten metal, usually a bronze composition, 80 is then poured into the matrix in well known manner and flows outward against the inner face of the band, embedding the inwardly projecting shanks 5 of the vanes solidly and integrally within the metal of the circular 85 rim 7 of the wheel. The cast metal, as it flows against the band 20, effects an integral weld with the shanks 5 and with the inner face of the band; since said band is sufficiently thin to avoid chilling as the molten 90 metal comes in contact therewith; the exterior of the band being against the core substance, preserves its original shape and surface. 95

As results of the method hereinbefore described the manufacture of turbine rotors is facilitated and simplified, and the practice rendered more economical, convenient and efficient; the vanes are readily and conveniently assembled in the band while the latter is maintained in true circular form by the supporting clamps, and their accurate relation thereby then fixed while all are externally incorporated, as a unitary member, within the encasing annulus of core material 100 that may be transported, stored or handled as desired. The vanes are held in such manner by the annulus that the shrink of the casting when cooling does not strain or displace vanes in the cast rim; since any strain 105 movement is accommodated by and within the core-material substance. 110

I claim and desire to secure by Letters Patent:

1. The method of making turbine rotors, 115 which consists in primarily arranging the perforated metal band upon the periphery of a pair of adjacent circular clamp-plates, assembling therewith vanes having reduced shanks and transverse shoulders, said vanes 120 disposed in their required order with their reduced shanks inserted through said perforated metal band and projecting inward between said clamp-plates, rigidly securing the inwardly projecting shank portions of 125 all the vanes between and by means of said clamp-plates, within the circle of said band, placing said clamp-plates with the assembled band and vanes concentrically within an annular core-box and forming about the pe- 130

periphery of the clamp-plate a complete unitary ring of core-material enveloping and embedding the said vanes and metal-band, removing the clamp-plates and embedded parts from the core-box, releasing the clamp-plates from the inwardly projecting shanks, leaving the cylindrical annulus containing the vanes and band adapted for placement within a suitably shaped mold for casting the rotor-wheel body within said annulus.

2. In the method of making turbine rotors, wherein the radial vanes have their shanks arranged through apertures in an annular band; the improvement which consists in primarily supporting the band in cylindrical form and confining the full series of assembled vanes by a plurality of circumferentially circular clamp-devices applied to and closed upon the shanks of the vanes within the circle of the band; forming about said circle a complete enveloping annulus of core-material baked upon the outward projecting vanes and externally embracing said band; then removing the clamp devices from the shanks, and casting a member to embed said inward projecting shanks and to unite integrally with said vanes and band, and subsequently breaking out and removing the annulus of core-material.

3. In the art of making turbine rotors, comprising a series of vanes assembled with a smooth-faced flexible band having spaced apertures through which the shanks of the vanes are inwardly projected; the method which consists in primarily supporting the band upon the cylindrical periphery face of adjacently disposed clamp-plates, assembling the series of vanes therein with their shanks projecting inward between said clamp-plates; temporarily confining the shanks and vanes rigidly in their assembled relation by closure of said clamp-plates, forming around the exterior face of said band and enveloping the outward radially projecting ends of the entire series of clamped vanes, a flat cylindrical encasing annulus of core-material compacted and baked thereon; then releasing the shank-confining means, and

subsequently casting a wheel member to embed said projecting shanks, and to unite integrally with said band.

4. In the method of making turbine rotors, including a continuous band-strip of thin metal approximately corresponding to the desired width of the rotor-wheel rim, and having a spaced series of perforations therethrough, the improvement which consists in arranging said band about the exterior circumferential face of a separable circular form, assembling therewith, in their properly positioned relation, a series of vanes having reduced shanks with said shanks inwardly projected through said band, then encasing the outward projecting part of the vanes, adjacent the outer face of the band, with plastic core-material to form a complete surrounding core annulus, treating said core annulus to render the same sufficiently rigid for handling as a unitary ring; and for maintaining the assembled parts in positively fixed relation therein after the separable circular form has been removed from the interior of the band.

5. The herein described method in making a turbine rotor, which consists in temporarily supporting a series of turbine vanes having their shanks inwardly projected through apertures in a thin circular band, by a circular separable clamping means, the circumferential face of which forms a support for said band, disposing said clamping means within a cylindrical receptacle and compacting therein about the vanes and band an encasing-body of plastic core-material forming a complete annulus, drying and hardening said core-material to solid condition upon the vanes, and then releasing the clamping means therefrom; thereby affording a unitary annular vane-retaining member adapted for convenient handling and for ready insertion in the matrix of a wheel-casting mold.

Witness my hand this 20th day of February, 1918.

AXEL W. CARLSON.
